UNITED STATES PATENT OFFICE

SIGMOND G. WEILER, OF MILWAUKEE, WISCONSIN

BRUSH

Application filed October 30, 1929. Serial No. 403,584.

This invention pertains to brushes, and is designed for particular use in connection with garments, drapes, upholstery, and the like.

5 It is well recognized that steaming and brushing various kinds of cloth, such as velvet, velour, woolen, worsted, and other nappy materials, results in more thoroughly cleaning the same and entirely renewing 10 their appearance by raising the nap to its original condition.

Heretofore, various types of steam brushes have been employed by the trade, but these have been expensive and beyond the reach of 15 the average individual.

It is, therefore, the primary object of the present invention to provide a simple and inexpensive brush with means for spraying a garment or the like, with steam during 20 the brushing operation, and which is controlled by the operator without removing his hand from the brush.

Incidental to the foregoing, a further object is to provide an inexpensive brush structure with a steam nozzle connected with any 25 convenient source of steam supply, such as a tea kettle or other conventional cooking vessel, by means of a flexible hose or tube, the steam jet being controlled by a valve carried by the brush handle, and the nozzle being so positioned with relation to the bristles of the brush as to cause the steam spray to thoroughly spread over the material before condensation takes place, thus avoiding 30 undue saturation.

A more specific object resides in the provision of a brush of the foregoing character in which the steam supply pipe is embedded in a handle formed of wood or other inexpensive material which is a non-conductor of 40 heat, the control valve for the steam supply pipe being provided with a depressible actuating button protruding from one side of the handle to allow convenient operation by 45 the operator while brushing a piece of material.

With the above and other objects in view, which will appear as the description proceeds, the invention resides in the novel construction, combination and arrangement of 50

parts substantially as hereinafter described and more particularly defined by the appended claim, it being understood that such changes in the precise embodiment of the herein disclosed invention may be made as come within the scope of the claim. 55

In the accompanying drawings is illustrated one complete example of the physical embodiment of the present invention constructed according to the best mode so far devised for the practical application of the principles thereof. 60

In the drawings, Figure 1 is a side elevation of a brush constructed in accordance with the present invention; 65

Figure 2 is a section taken on the line 2—2 of Figure 1 with parts broken away to more clearly illustrate structural features; and

Figure 3 is a transverse section taken on the line 3—3 of Figure 1. 70

Referring now more particularly to the accompanying drawings, the numeral 1 designates a conventional brush back having embedded therein the bristles 2. Secured to the back 1 in any suitable manner, such as the pins 3 illustrated, is a handle 4 preferably formed of wood, because of its cheapness, but which may be made of any material that is a good non-conductor of heat. 75

The handle 4 is provided with a longitudinal bore 5 in which is positioned a steam supply pipe 6 provided with a coupling 7 for connecting a flexible tube or hose 8, the latter being connected with any suitable source of steam supply, such as an ordinary tea kettle or the like. 80

Adjacent the forward end of the brush and communicating with the bore 5, the handle 4 is provided with a recess 9 for reception of a valve 10 secured to one end of the pipe 6. 90 As best seen in Figure 2, the recess 9 is provided with a lateral extension 11 which receives a portion of the valve 10 that carries the actuating button 12. The actuating button extends through an opening 13 communicating with the lateral extension of the recess 9 and protrudes beyond the side of the handle, where it may be conveniently actuated by the operator without shifting or removing his hand from the brush. Obvi- 95 100

ously, the button 12 would preferably be formed of material which is a non-conductor of heat.

- Secured to the forward end of the valve 10 and projecting from the handle 4 is a nozzle 14 which is directed downwardly toward the bristles but terminates short of the plane of the face of the bristles in order that the spray of steam will spread sufficiently over the material to be brushed, prior to condensation, thus insuring a thorough saturation of the steam in the material without excessive moisture. The brush and parts thereof may be readily assembled by inserting the valve member 10 in the recess 9 with button 12 projecting through opening 13. The steam supply pipe 6 can then be passed through the longitudinal bore 5 and engaged with the valve member. The nozzle 14 can be inserted 15 through the opening provided therefor in the handle and also engaged with the valve and the brush back 1, and can then be attached to the handle for closing the recess 9 and retaining the valve member therein.
- From the foregoing, it will be readily seen that a very simple, inexpensive brush has been provided which because of its cheapness is within reach of the average individual for domestic use, and which enables the operator 20 to simultaneously steam and brush a piece of material, the steam supply being conveniently controlled by the depressible button without shifting the operator's grip upon the brush.

35 I claim:

- In a brush for steaming fabrics, the combination with a brush back carrying a plurality of bristles on one face thereof, a manipulating handle formed of non-heat conducting material secured to the opposite face of the brush back having a T-shaped recess and longitudinal bores communicating with the opposite ends of the recess and a transverse bore communicating with the recess 40 intermediate its ends, a steam conducting pipe disposed in one longitudinal bore and terminating in said recess, a T-shaped valve casing fitted in the recess connected with the steam conducting pipe, a valve therein, 45 a manipulating button for the valve casing extending exteriorly of the handle through the transverse bore, and an arcuate steam outlet pipe extending through the other longitudinal bore and connected with the valve fitting, said steam outlet pipe extending downwardly and forwardly in front of the brush bristles.

In testimony that I claim the foregoing I have hereunto set my hand at Milwaukee, in 50 the county of Milwaukee and State of Wisconsin.

SIGMOND G. WEILER.
